UNITED STATES PATENT OFFICE.

JOEL L. ISAACS, OF MILWAUKEE, WISCONSIN.

BED-SPRING.

1,388,261.

Specification of Letters Patent. Patented Aug. 23, 1921.

Application filed July 23, 1920. Serial No. 398,519.

To all whom it may concern:

Be it known that I, JOEL L. ISAACS, a citizen of the United States, residing at Milwaukee, in the county of Milwaukee and State of Wisconsin, have invented certain new and useful Improvements in Bed-Springs, of which the following is a specification.

One style of bed-spring on the market comprises a plurality of longitudinal, parallel, spaced, relatively-narrow, flat, metal strips or bands connected to the ends of the frame by helical springs and desirably cross connected together by similar shorter springs. Such a construction, while convenient and advantageous from many aspects, nevertheless has a distinct disadvantage in that it leaves a large number of gaps or spaces between the strips into which portions of the superposed mattress sag, and when it is desired to turn the mattress over or reverse it end for end, as is frequently necessary, difficulty is encountered in freeing the mattress from such strips of the fabric with which it has become more or less interlocked by reason of such depressed or sagging sections. To turn a mattress over, it is first necessary to draw or pull it crosswise the spring, whereupon the overturning operation may be effected. But with a bed-spring of the character specified, such sliding of the mattress over the spaced slats or strips is effected only with difficulty and inconvenience because of the relatively sharp bends in the mattress about the longitudinal edges of the metal strips.

The leading object and prime purpose of the present invention is the production or provision of an improved form of bed-spring of the general type specified, which will facilitate the turning over or reversal of the mattress and in which the metal strips or slats are somewhat stiffened for strengthening purposes.

In order that those skilled in this art may have a full understanding of this invention and its various advantages and may comprehend the manner in which the above-specified and other desirable objects are attained, I have illustrated in the accompanying drawing forming a part of this specification several desirable embodiments of the invention.

In this drawing—

Figure 1 is a perspective view of the entire bed-spring; 55

Fig. 2 is an enlarged cross-section through a few of the metal strips;

Fig. 3 is a similar view of a modified construction; and

Fig. 4 is a like illustration of still a further style of metal strip.

As is clearly illustrated in this drawing, the bed-spring comprises the usual frame composed of end-bars 10, 10 and side rails or bars 11, 11, the end-bars supporting a relatively large number of spaced, parallel, metal bands or strips 12, 12 by means of helical-springs 13, 13 fastened to the end-bars in the usual way and also secured to the ends of such strips, the latter being also connected together yieldingly crosswise or transversely of the appliance by other short coil-springs 14, 14, so that the top or fabric of the bed-spring as a whole possesses adequate resilient or cushioning characteristics 75 to perform the functions for which the appliance is intended. As is shown more clearly in Fig. 2, the metal strips 15 at the edges of the spring are appropriately wider than the intermediate companion members 12 to 80 strengthen such portions of the structure which are subjected to greater strains, and as is customary such border strips are secured to the end-bars of the frame by a pair of helical springs 13 instead of a single 85 spring.

In order to prevent the superposed mattress from becoming objectionably and detrimentally interlocked with such metallic fabric as indicated above, the metal strips or bands are bent or arched or bowed slightly transversely to relieve or eliminate the sharp bends at those portions of the mattress which sag or project downwardly into the spaces between and around the edges of such metallic bands. The entire width of each metal band or strip 12 and 15 may be laterally arched or curved as shown in Fig. 2 or its middle portion only may be curved crosswise as shown in strips 16 in Fig. 3, 100 and in each instance the sharp bend or deflection of the mattress around the edges of the metal bands is avoided so that the mattress may without difficulty be pulled cross-

wise the structure while resting thereon thus facilitating the overturning operation. By thus shaping these bands or strips such desirable result is not only accomplished but 5 the bands are also somewhat strengthened or stiffened by reason of this new conformation.

As illustrated in Fig. 4, the main body of these bands 17 may be flat with their 10 edges curved or bent downwardly providing flanges, as shown, which give to such bands or strips the specified desirable characteristics with respect to the easy sliding of the mattress crosswise thereover and the stiffening or strengthening of such bands.

Although in this application I have set forth in detail only a few embodiments of the invention, it is to be understood that the latter is not limited and restricted to the precise and exact details of structure shown and described because these may be modified within comparatively wide limits without departure from the heart and essence of the invention and without the sacrifice of any of 25 its substantial benefits and advantages.

Although this invention has been illustrated and described in connection with the bed-springs, it is obvious that an invention of this character may be satisfactorily employed in other but somewhat different 30 fields, *i. e.*, cushions, chair seats, couches, etc.

I claim:

In a cushion structure of the character described, the combination of a frame, and a metallic fabric thereon comprising in combination a plurality of lengthwise-disposed, transversely upwardly arched spaced, parallel, sheet-metal bands, springs connecting said bands at their ends to said frame, means connecting said bands together transversely between their ends, the top faces of said bands and the tops of said intermediate connecting means being in substantially the same horizontal plane, the curved shape and the location of the top surfaces of said 40 bands facilitating the transverse sliding of the superposed mattress thereon, substantially as described.

JOEL L. ISAACS.
